UNITED STATES PATENT OFFICE

172,927

AIRPLANE

Clarence L. Johnson, Encino, and Willis M. Hawkins, Jr., North Hollywood, Calif., assignors to Lockheed Aircraft Corporation, Burbank, Calif.

Application December 31, 1953, Serial No. 28,301

Term of patent 14 years

(Cl. D71—1)

To all whom it may concern:

Be it known that we, Clarence L. Johnson and Willis M. Hawkins, Jr., both citizens of the United States, residing at Encino and North Hollywood, respectively, in the State of California, have invented a new, original, and ornamental Design for an Airplane, of which the following is a specification, reference being had to the accompanying drawings, forming a part hereof.

Figure 1 is a perspective view of an airplane showing our new design;

Figure 2 is a top plan view thereof;

Figure 3 is a side elevational view thereof;

Figure 4 is a front elevational view thereof;
and

Figure 5 is a bottom perspective view thereof.

This application is a continuation-in-part of our prior design application Serial No. D.19,928, filed May 28, 1952, for an Airplane, now abandoned.

The essential features of our design reside in the portions shown in full lines.

We claim:

The ornamental design for an airplane, as shown and described.
